COMBINED SHUTTLE FEELER AND THREAD CUTTER

Filed July 22, 1929

UNITED STATES PATENT OFFICE

AUGUSTIN J. CHEVRETTÉ, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

COMBINED SHUTTLE FEELER AND THREAD CUTTER

Application filed July 22, 1929. Serial No. 380,181.

This invention relates to improvements in combined thread cutters and shuttle feelers and it is the general object of the invention to provide a device of this kind which will 5 automatically move toward the selvage to prevent the weft end from pulling away from the clamp.

In weft replenishing looms more particularly of the multicolor type it is customary 10 to employ a vertically movable shuttle feeler which is lifted by an improperly placed shuttle to prevent transfer. When a thread cutter and clamp is placed on a feeler of this type there is a tendency for the weft end 15 of the outgoing bobbin to pull out of said clamp, particularly where the weft is inelastic. It is an important object of my present invention to pivot the shuttle feeler so that the same may move toward the selvage when 20 being raised to normal position.

It is a still further object of my present invention to provide a shuttle feeler pivoted to move in a horizontal plane and having a 25 cam slot therein to cooperate with a fixed operating pin, the slot having a dwell which will be effective to prevent horizontal motion of the shuttle feeler until the latter has had sufficient upward motion to perform its function of detecting for a misplaced shuttle and 30 revoking transfer. It is a further detail of my invention to permit adjustment of the operating member so that by means of it the time of beginning the horizontal motion of the feeler may be varied.

With these and other objects in view which will appear as the description proceeds, my invention resides in the combination and arrangement of parts hereinafter set forth and 35 described in the claims.

In the accompanying drawings wherein a convenient embodiment of my invention is set forth,

Fig. 1 is a side elevation from the interior 45 of the loom showing my invention in normal or raised position, the lay being shown in section,

Fig. 2 is a perspective view from the central front portion of the loom showing the 50 invention in the position set forth in Fig. 1,

Fig. 3 is a vertical section on line 3—3 of Fig. 1,

Fig. 4 is a top plan view taken in the direction of arrow 4, Fig. 1 and

Figs. 5, 6 and 7 are diagrammatic views 55 showing the shuttle feeler in down, intermediate and normal or raised positions, respectively.

Referring to Fig. 1, I have shown a magazine of the usual multicolor construction embodying a frame 10 having a foot 11 which is supported by a loomside 12. A transerrer arm 13 is movable in an arcuate slot 14 by means of connections not shown but operated by the lay.

Near the rear of the magazine is a stand 15 which supports a stud 16 having adjustably secured thereto for angular movement an upstanding arm 17 provided with a slot 18. A stud 19 is secured in adjusted longitudinal position along the slot and affords pivotal connection for the upper end of an operating rod 20 adjustable as to length.

Extending substantially parallel to the stud 16 and held to the bracket or stand 15 is 75 a second stud 21 on which is rotatably mounted the hub 22 of a shuttle feeler mechanism. This hub is pivotally connected as at 23 to an upwardly extending control rod 24. The shuttle feeler comprises a holder 25 in which 80 is secured by means of bolt 26 a pressed steel arm 27 having a lower arcuate surface 28 adapted to engage the nose of a misplaced shuttle. The shuttle feeler is operatively connected to the rod 20 and moves with the latter in a vertical direction.

The lower forward end of the shuttle feeler has pivoted thereto as at 29 a movable cutter blade 30 having an upstanding finger 31 which is attached pivotally to the lower 90 end of rod 20. A portion of the shuttle feeler may be ground to provide one of the cutting edges of a cutter mechanism to cooperate with the rearwardly extending jaw 32 of the cutter element 30. A thread clamp 33 is secured to the shuttle feeler and normally bears against the jaw 32, the latter being between the clamp and the body of the shuttle feeler.

In the operation of the mechanism thus far 100

described the rod 24 is normally in raised position, being held so by mechanism not shown but well understood and set forth in patent to Ryon No. 1,030,748. In this position the jaw 30 is as illustrated in Fig. 1, being closed and cooperating with the clamp 33 to hold a weft end between the clamp and jaw 32. At the time transfer is to take place the control rod 24 will be depressed to move the hub 22 in a right hand direction as viewed in Fig. 1 around stud 21, thereby lowering the shuttle feeler 27 into the path of the shuttle S carried by the lay L. Inasmuch as the stud 19 is fixed, the downward motion of the shuttle feeler will open the jaw 32 through the action of the rod 20. Should the shuttle be misplaced during the forward movement of the lay on which transfer is to take place it will engage the surface 28 and lift the shuttle feeler, thereby causing an upward movement of the control rod 24. By mechanism not shown but set forth in the aforesaid Ryon patent upward movement of this rod 24 is effective to prevent transfer.

The matter thus far described of itself forms no part of my invention except the manner of mounting and otherwise constructing the holder 25, the arm 27 being substantially the same as shown in prior patent to Robb No. 1,689,688, and the cutter and rod 20 being substantially the same as set forth in my prior Patent No. 1,662,235.

As previously stated, it is desirable to provide means whereby a relatively inelastic weft end extending from the clamp 33 to the selvage may be slackened to prevent pulling away from said clamp, and to accomplish this result I provide the holder with a hub 40 which extends between upper and lower ears 41 and 42, respectively formed on the hub 22. Extending between and secured to said ears is a pivot pin 43 forming a pivotal support for the hub 40 and therefore the shuttle feeler, permitting the latter to move in a horizontal direction toward and from the selvage. As set forth herein I form the holder 25 with a rearwardly extending cam arm 44 having therein a slot 45 to receive a finger 46 formed as part of an operating member 47 mounted on the stud 21 and secured in the adjusted angular and longitudinal position thereon by means of set screw 48. The finger extends into the slot far enough to cause horizontal movements of the shuttle feeler in a manner to be described. As shown herein I have placed the pin 46 somewhat behind the vertical axis of the stud 43.

In operation, when the shuttle feeler is in its normal raised position the pin 46 will occupy the front end of the slot 45 and the shuttle feeler will be relatively near the selvage. During the first part of the downward movement previously described the inclined portion 49 of the slot 45 will cooperate with fixed pin 46 to cause the shuttle feeler to

move away from the selvage. At an intermediate point in the descent of the shuttle feeler the pin 46 will enter the straight portion 50 of the slot which is in a vertical plane substantially perpendicular to the axis of stud 21. After the pin 46 enters the straight portion of the slot there will be no further horizontal motion of the shuttle feeler, the latter moving downwardly to shuttle feeling position.

During the forward beat of the lay following the lowering of the shuttle feeler the cutter and clamp will be in position to receive the thread which extends from the selvage to the outgoing bobbin. Should the shuttle be misplaced the nose thereof will engage the surface 28 as previously described and raise the feeler to revoke transfer, the revoking operation being concluded while the pin 46 is still in the straight portion 50 of the slot 45. In this way I retain the necessary function of the shuttle feeler and require the latter to move in a vertical plane while in engagement with a misplaced shuttle.

Should the shuttle be properly positioned, however, the box back 51 will engage the surface 28 and lift the shuttle feeler. Under these conditions the cutter and clamp will be in a position near enough the reed line of the loom to receive the thread of the outgoing bobbin. As the shuttle feeler rises the cutter and clamp will operate as set forth in my aforesaid patent through action of the rod 20 and the fixed support therefor. During the latter part of the upward movement of the shuttle feeler the pin 46 will enter the inclined portion 49 of the groove 45 and start to move the shuttle feeler toward the selvage. During upward movement of the unit, the rod 20 is able to move laterally due to the looseness of the headed end of the rod which has contact with the stud 19.

The positions previously described are set forth diagrammatically in Figs. 5, 6 and 7, Fig. 5 showing the relation of the pin 46 and straight portion 50 of the slot when the shuttle feeler is all the way down in feeling position, Fig. 6 showing the relation when the shuttle feeler is in an intermediate position during its upward movement with the pin 46 in position to leave the straight and enter the inclined portion of the slot, and Fig. 7 showing the normal relation of the operating pin of the slot when the shuttle feeler is raised.

I find that a motion constructed as set forth herein can be successfully used with non-elastic filling. When the shuttle feeler is in its lowest position it is substantially in the same horizontal plane with the cloth and there is very little tendency for the thread to pull out of the clamp during that part of the upward movement of the shuttle feeler when the pin 46 is in the straight portion 50 of the slot. During the latter part of the upward movement of the shuttle feeler, how-

ever, when the distance between the clamp and the selvage increases more rapidly the inclined slot 49 is operative to move the shuttle feeler toward the cloth to effect a slackness and prevent the inelastic weft from pulling away from the clamp.

I am aware that it has been proposed heretofore to employ pins and cam slots to effect movement of the shuttle feeler toward the selvage, but so far as I am aware these devices have operated to move the shuttle feeler and cutter together as a whole in a parallel motion. The upward movement of the shuttle feeler is comparatively limited and as a result the movement permissible in these earlier devices has been insufficient. By pivoting the shuttle feeler to its hub as set forth herein I am able to multiply the motion of the clamp and cutter so that a greater slackening is possible than in the devices referred to. The multiplication of the motion depends upon the distance between the axes of the stud 43 and the pin 46.

From the foregoing it will be seen that I have provided a combined shuttle feeler, thread cutter and clamp which is pivoted to move in a vertical position to effect shuttle feeling and also in a horizontal direction to slacken the weft end held by the clamp. It will also be noted that the shuttle feeler is required to move in a vertical plane only during the first part of its upward movement, thereby permitting the same to operate satisfactorily as a shuttle feeler. This part of the motion occurs when the rate of movement of the thread clamp away from the selvage is a minimum. It will also be seen that when the rate of movement of the clamp away from the selvage becomes relatively high the portion 49 of the slot becomes effective to cause a movement of the thread clamp toward the selvage.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a shuttle and a combined shuttle feeler and thread cutter and clamping unit pivoted above and behind the lay when the latter is in its forward position, a fixed operating member, and a lever device to cooperate with the operating member supporting said unit and movable in a vertical plane to effect shuttle feeling and movable in a horizontal plane under influence of the operating member to cause the thread clamp to move toward the selvage, a holder for the unit movable vertically pivotally connected thereto, said fixed means to cooperate with the unit and effective during vertical motion of the holder to cause

pivotal movement of the unit in a direction toward the selvage.

2. In a weft replenishing loom having a shuttle and a combined shuttle feeler and thread cutter and clamping unit pivoted above and behind the lay when the latter is in its forward position, a fixed operating member, and a lever device to cooperate with the operating member supporting said unit and movable in a vertical plane to effect shuttle feeling and movable in a horizontal plane under influence of the operating member to cause the thread clamp to move toward the selvage, a holder for the unit movable vertically pivotally connected thereto, 80 a cam operatively connected to the unit, said cam and member effective during the upward movement of the holder to cause movement of the unit relatively to the structure in a substantially horizontal direction toward the 85 selvage.

3. In a weft replenishing loom, a thread cutter and clamping unit, a supporting stud fixed with respect to the unit, a hub mounted on the stud, a lever held normally fixed to 90 the magazine, a connection between the magazine and hub and at transfer said connection giving the hub an operative vertical movement, a normally stationary member fixed to the stud and having operative engagement with the unit, a second connection between the unit and lever whereby the cutter is moved from inoperative to operative position as the unit moves vertically and inter-engaging connections between the hub 100 and unit and fixed member and unit whereby a movement of the hub in a vertical plane will cause a combined vertical and horizontal movement of the unit.

4. In a weft replenishing mechanism for 105 a loom, a thread cutter and clamping unit, a stud fixed with respect to the replenishing mechanism, a hub loose on the stud, said unit having pivotal connection with the hub so that the latter may move in a horizontal 110 plane, a member normally fixed with respect to the stud, a connection between the hub and magazine and at transfer said connection giving the hub a vertical movement, means defining a cam slot in the unit, and operative 115 connections between the slot and member whereby a vertical movement of the hub will tend through the slot and connection to the member to give the unit a horizontal movement.

In testimony whereof I have hereunto affixed my signature.

AUGUSTIN J. CHEVRETTE.
